(57) **CLAIM**

I claim the ornamental design for a form bracket for a concrete panel form, as shown and described.

DESCRIPTION

FIG. 1 is a front, top, and right perspective view of a form bracket for concrete panel form;

FIG. 2 is a rear, bottom, and left perspective view thereof; FIG. 3 is a right view thereof, the left view being a mirror image of the right view;

FIG. 4 is a cross-sectional view thereof, taken at line IV-IV in FIG. 5;

FIG. 5 is a front view thereof; and,

FIG. 6 is a rear view thereof.

In the drawings, broken lines of equal length (e.g., dash-dot) represent unclaimed subject matter and form no part of the claimed design. Broken lines of unequal length (e.g., dash-dot-dot) define bounds of the claimed subject matter and form no part of the claimed design.
